[57] CLAIM

The ornamental design for a bowl, substantially as shown and described.

DESCRIPTION

FIG. 1 is a top plan view of a bowl showing my new design;

FIG. 2 is a front elevational view thereof;

FIG. 3 is a bottom plan view thereof;

FIG. 4 is a side view thereof; and

FIG. 5 is a perspective view thereof.

The side opposite to that shown in FIG. 4 is substantially a mirror image thereof.
